(57) CLAIM

The ornamental design for a pair of removable face plates of a video game controller, as shown and described.

DESCRIPTION

FIG. 1 is a perspective view of a pair of removable face plates of a video game controller showing our new design;

FIG. 2 is a front elevation view thereof;

FIG. 3 is a rear elevation view thereof;

FIG. 4 is a right side elevation thereof;

FIG. 5 is left side elevation thereof;

FIG. 6 is top plan view thereof; and,

FIG. 7 is a bottom plan view thereof.

The broken lines shown in the figures are for illustrative purposes only and form no part of the claimed design.
